UNITED STATES PATENT OFFICE.

GEORGE W. DOVER, OF CRANSTON, RHODE ISLAND.

PIN.

1,077,599.

Specification of Letters Patent.

Patented Nov. 4, 1913.

Application filed December 14, 1911. Serial No. 665,758.

To all whom it may concern:

Be it known that I, GEORGE W. DOVER, of Cranston, in the county of Providence and State of Rhode Island, have invented certain new and useful Improvements in Pins; and I do hereby declare the following specification, taken in connection with the accompanying drawings, forming a part of the same, to be a full, clear, and exact description thereof.

The invention relates to pins of the class commonly known as dress or bar-pins, and has for its object to provide pins of this character with a double or dual catch, the opening in one of said catch members being upon the opposite side from the opening in the other of said catch members.

To this end the invention consists of the novel combination and arrangement of parts hereinafter described and more specifically set forth in the claims, reference being had to the accompanying drawings, in which—

Figure 1 is a perspective view of my novel form of pin in closed position. Fig. 2 is a side view of the same. Fig. 3 is a top plan view. Fig. 4 is a sectional view on line $x-x$, Fig. 2. Fig. 5 is a sectional view on line $y-y$, Fig. 2.

Referring to the drawings, 1 represents the front portion of the pin which is secured to the back plate 2 by rolling the edge of said front plate over the edge of said back plate. The back plate 2 is provided with a hinge member 3 adjacent one end and a catch member 4 adjacent the other end. Mounted to swing in the hinge member 3 is a pin-tongue 5, the pointed end of which is adapted to engage the catch member 4 through an opening 6 in one side thereof. Mounted upon the back plate 2 between the hinge-member 3 and the catch member 4 is a second catch-member 7 which is provided with a curved slot 8 upon the opposite side from the slot 6 in the catch member 4.

In applying the pin, the pin-tongue 5 is run through the fabric in such a manner that the portion of said pin-tongue opposite the catch member 7, as well as the pointed end, will be exposed. Said pin-tongue 5 is then

snapped into the curved slot 8 in the catch 7. 50 This operation brings the pointed end of the pin-tongue against the closed side of the catch member 4. Said pointed end of the pin-tongue is then passed over the top of the catch-member 4 and through the opening 6 55 into engagement with said catch member. It will be seen that in passing the pointed end of the pin-tongue 5 over the top of the catch member 4 of the portion of the pin-tongue 5 which engages the slot 8 in the catch 7 will 60 be passed against the inner end of said slot and a spring action will be set up in the pointed end that will cause it to spring into the opening 6 in the catch member 4 and to be held in place therein. 65

With the above construction it will be seen that the catch 7 not only acts as a support to prevent the pin-tongue from being bent and pulled lengthwise out of the catch-member 4, but also serves to lock the pin-tongue in position in both catch members, so that it cannot become accidentally disengaged from either by any undue strain upon either side of the pin. It will also be seen that the bottom edge of the slot 8 prevents the pin-tongue 75 from any movement toward the back plate 2 and that said pin-tongue is locked against movement in every direction.

What I claim as my invention and desire to secure by Letters Patent is:

1. An article of the character described comprising a body portion, a pin-tongue hinged thereon, a catch member provided with an opening on one side adapted to receive the pointed end of said pin-tongue, and a second catch member provided with a slot located upon the opposite side from the opening in said first catch member, the closed end of said slot being in line with the upper interior wall of said first catch member. 80 85 90

2. An article of the character described comprising a body portion, a pin-tongue hinged thereon at one end, a catch member at the opposite end provided with an opening on one side, a second catch member intermediate the ends and provided with a curved slot oppositely disposed to the opening in said first catch member, the inner end of 95

said slot being in line with the upper interior wall of said first catch member.

3. An article of the character described comprising a body portion, a pin-tongue hinged thereon at one end, a catch member at the opposite end, and a support intermediate the ends having a transverse slot in line with said catch member and adapted to

prevent any movement of the pin-tongue toward the back-plate when the pin is in closed position. 10

GEORGE W. DOVER.
